UNITED STATES PATENT OFFICE

2,250,066

MUSICAL INSTRUMENT

James Manatt, Chicago, Ill., assignor to Central Commercial Company, Chicago, Ill., a corporation of Illinois

Application July 17, 1940, Serial No. 345,928

15 Claims. (Cl. 84—1.17)

This invention relates to electrical musical instruments of the class in which tone signals may be selectively translated into acoustic energy of any desired waveform and same has particular reference to instruments employing a series of electron discharge devices coupled together in cascade so that the output signal from any device is harmonically related to the output signal of the next preceding device of said series.

Certain frequency dividing systems with which I am acquainted employ relaxation oscillators comprising "glow discharge" or "gas content" tubes electrically coupled together in cascade fashion to lock the tubes in step and obtain octave separation of their respective output signals, the first stage tube functioning in the system to control the input frequency of the next preceding tube. Other systems comprise non-oscillatory dividing circuits in which "vacuum" tubes, including a first stage tube are interconnected in cascade, likewise to obtain octave separation of their respective output signals, the first stage tube, however, receiving a controlling signal from an oscillating circuit which contains a "master" oscillator.

In frequency dividing systems which are the same or substantially similar to the aforementioned prior systems, it has been impossible to stabilize the output frequencies of the tubes or lamps employed and accurately to obtain octave separation of said frequencies, due, largely, to variations in the circuit constants resulting from mechanical vibration, thermal and humidity effects, recognized instability of the tube elements, and various other causes.

Certain important objects of my invention are as follows:

To provide an organization of elements functioning to overcome the aforementioned existing defects in frequency dividing systems and otherwise to improve upon said systems to the end that new and superior results are obtained.

To provide an oscillatory frequency dividing circuit in which the oscillators are interconnected in cascade in a manner definitely to lock said oscillators in step with each other and secure octave separation of their respective output signals.

To provide means including a non-oscillatory controlling circuit for the first stage oscillator of a series of similar oscillators connected together in cascade, said means serving in a highly reliable manner always to transmit to said first stage, a controlling signal of invariable fundamental frequency.

5 To provide in combination with different sets of similarly cascaded oscillators, means other than frequency generators of the "vacuum" or "gas content" type for simultaneously and continuously producing fundamental frequencies and utilizing said frequencies to control the first stage oscillators of all sets of said similarly cascaded sets of oscillators.

To provide a highly reliable and exceedingly simple electro-mechanical controlling system for continuously generating musically related tone signals and simultaneously utilizing said signals to control all first stage oscillators of a plurality of similar sets of cascaded oscillators wherein the oscillators of each set respectively produce tone signals in octave relation.

To provide a musical instrument in which tone signals for a musical scale tuned in equal temperament are generated by similar oscillators.

10 20 To provide a musical instrument having means other than vacuum tubes or like electron discharge devices for generating controlling signals of invariable frequency and continuously utilizing said signals to control and stabilize the frequencies of "vacuum" tube oscillators.

25 To provide an electrical musical instrument having simple and reliable mechanism for electro-magnetically generating controlling signals and utilizing said signals to control the first stage oscillators of different sets of similar oscillators.

30 35 To provide an electrical musical instrument having means for inductively generating controlling signals by the relative motion of coacting parts of alternators and periodically varying the frequency of said signals and similarly periodically varying the frequency of the output signals of all oscillators, whereby true vibrato effects can be selectively produced.

40 45 To provide an electrical musical instrument which remains in tune over long operating periods of time and will not get out of tune as a result of shocks and jars transferred to its operating parts during transportation of the instrument and will not be subject to temperature and humidity conditions.

50 To provide a light weight and readily portable electrical musical instrument capable of accommodation in a small space and yet have the musical range of a large and less portable instrument.

55 To provide an electrical musical instrument consisting of a simplified organization of coacting elements for producing many pleasing musical results.

To provide an electrical musical instrument capable of closely simulating pipe organ tones.

To provide an electrical musical instrument in which a definite pitch relation is maintained between tone signals simultaneously and continuously generated, the retention of said pitch relation being due largely to the invariable rotational speed of a single motion transferring element which is common to corresponding driven parts of similar alternators.

To provide an electrical musical instrument in which the means for simultaneously and continuously generating controlling tone signals of invariable frequency embodies means in coaction therewith enabling the frequency of the generated signals to be varied periodically without changing the rotational speed of the aforementioned motion transferring element.

To provide an electrical musical instrument having oscillators coupled together in cascade to produce harmonically related output signals, the voltage levels of which are equal, thereby rendering unnecessary use of voltage regulators heretofore required for regulating the relative amounts of effective voltage musically necessary for correctly voicing the instrument.

To provide an exceedingly simple and compact mechanism which has none of the disadvantages of "master" oscillators, "vacuum" tubes, "gas content" lamps, vibratile controlling devices, etc., the same continuously functioning to produce signals corresponding to the vibration frequencies of notes of the even tempered musical scale.

To provide a simple and inexpensive system of signal generators in which the rotational speeds of all generators are properly synchronized and cannot get out of step with each other, the result being that the pitch relation of the produced signals remains constant, notwithstanding occasional changes in line voltage.

Other objects and advantages of my invention will be more fully stated hereinafter and it is understood that I intend to claim as my invention all parts in their legitimate combinations as well as various sub-combinations of the various legitimate combinations, and also to claim as my invention certain of the parts and mechanisms per se.

The invention will be readily understood from the following description and the accompanying drawings wherein certain preferred embodiments of the invention are shown and in which:

Figure 1 is an oscillator of a series of similar oscillators employed in my improved frequency dividing system.

Figure 2 is an illustration of the waveform of voltage produced by the oscillator shown in Figure 1.

Figure 13 is a detail view of one of the frequency controlling wheels, and

Figure 14 is a schematic circuit diagram of means for controlling relative motion of coacting parts of the mechanism shown in Figure 5, whereby vibrato effects can be produced.

In Figure 1 an oscillator comprising a pentode tube of the remote cut off type is connected in an oscillatory circuit having a ground terminal 11, a terminal 12 adapted to be connected with a non-resonant input signal path as will be more fully pointed out hereinafter, and output terminals 13 and 14. The plate and the screen grid of said oscillator are supplied with direct current through resistors 4 and 6 in respective paths from a source of direct current shown at 2. Voltage from the source 3 is applied to the suppressor grid of the tube through a high resistance 8. This places a charge on said grid which is negative relative to the cathode and thereby limits the current drawn by the plate. Said negative charge on the suppressor grid produces a negative trans-conductance characteristic between the suppressor grid and the screen grid and the condition for oscillation is thereby obtained. In practice, satisfactory results are had with a source 2 providing 260 volts, a source 3 providing 16 volts, a resistor 4 of 250,000 ohms, a resistor 6 of 100,000 ohms, a resistor 7 of 10 ohms, a resistor 8 of 500,000 ohms, a fixed condenser 9 of the value of .05 mfd. and a fixed condenser 5, the value of which is of course calculated according to the frequency of the output signal desired to be obtained. Since this fundamental oscillator circuit functions as a trigger circuit when oscillating, and the condenser charge and discharge is periodic, the output signal from the tube will be approximately as shown in Figure 2.

When a controlling signal in the form of a minute alternating current is applied to the resistor 7, the voltage developed across the resistor is applied to the control grid of the tube. This modulates the electron flow within the tube and the tube is thus predisposed to oscillate at some multiple of the controlling frequency. It is therefore obvious that if the tube is tuned to oscillate at a frequency which is near a multiple or submultiple of the controlling frequency, it will oscillate in step with said controlling frequency.

Should it be desired to produce a substantially sinusoidal output signal as shown in Figure 4, resistances 27 and 29 and capacitors 28 and 30 are incorporated in the circuit illustrated in Figure 3, said circuit being otherwise the same in every respect as the circuit shown in Figure 1.

In Figure 7, I show eight oscillator stages, each stage connected in a circuit which is the same in every essential particular as the circuit shown in Figure 1. As the relative values of the resistances and the capacitors illustrated in Figure 7 are as stated in the description of Figure 1, it need merely be said that said eight oscillator

stages are electrically interconnected in cascade so as to lock said stages in step with one another and secure octave separation of their respective output signals.

It is assumed that the system of eight oscillators shown in Figure 7 is such that signals for all A# notes in the instrument's gamut will be produced. As the highest frequency or first stage oscillator receives a controlling signal from the pick-up magnet 49 of the A# disc of the signal generating system shown in Figure 5, the frequency of the output signal from said oscillator will be 7380 cycles per second.

Bridged across the path 80, as shown, is a suppressor circuit consisting of a capacitor 87 and an inductor 88, whereby undesired frequencies in said path will be shunted out from the input of the first stage oscillator 91 at the lower right hand side of Figure 7.

92 are plate resistors of uniform resistance value throughout the system; 94 the suppressor grid to screen grid coupling capacitors; 95 the screen grid resistors; 96 the suppressor grid resistors; 97 the control grid resistors; 98 the resistors in the resistance-capacitance filter stages and 99 the capacitance elements of said filter stages, the value of each of which will of course vary according to the frequency to be filtered. 100 is a capacitor for blocking direct current from the mixing circuits shown in Figures 8 and 9.

101 is a source of direct current which supplies the plate and screen currents for the respective oscillator stages and the negative biasing voltage for the suppressor grids.

102 is a common ground connection and 103 the capacitor for the first stage oscillator. Capacitor 104 serves the second stage, capacitor 105 the third stage and so on throughout the cascaded series of stages. These capacitors each connect indirectly to ground through the control grid resistor 97 of the following stage, with the exception of the capacitor 110 of the last and lowest frequency stage, the latter connecting directly to ground as at 102.

As the resistance 97 is low relative to any of the other resistances the frequency characteristics of the first stage oscillator are not appreciably disturbed by its insertion into the tuning circuit. However, a small potential drop at the frequency of the first stage occurs across the resistor and this voltage is applied to the control grid of the next succeeding oscillator stage. If the next succeeding stage is tuned by capacitor 104 to oscillate at approximately 3690 cycles, then, the small E. M. F. applied to the control grid will lock it into step with said first stage oscillator and it will generate exactly 3690 cycles or $\frac{1}{2}$ the frequency of said first stage oscillator. The capacitor 104 is connected to a corresponding control grid of the third stage and will lock it with respect to frequency if it is tuned by capacitor 105 to approximately 1845 cycles per second.

The electrical impulses for supplying controlling signals at the vibration frequencies of the notes of the even tempered musical scale are produced by a mechanism which comprises a synchronous motor 35 operating at 1800 R. P. M. and adapted to be supplied with potential through a wire 36 from a 60 cycle, 115 volt source of alternating current. Said motor is mounted upon an end wall 38 of a suitable metallic supporting frame, the latter grounded at g. The shaft 61 of the motor extends through said wall 38 and

is connected to a shaft 58 by a flexible coupling comprising elements 59 and 63 and an intermediate element 60 of resilient material such as rubber. The shaft is journaled in longitudinally aligned bearings 48 on partitions 40, 41 and an end wall 42 respectively of the aforementioned motor supporting frame and passes through longitudinally aligned bushings 41 on transverse yokes 43 of a magnet supporting frame, the latter comprising, in addition to said transverse yokes, a pair of parallel spaced apart side bars 44 situated inwardly of and spaced apart from the inner surfaces of the parallel side members 37 of said motor supporting frame, whereby said magnet frame is free to be tilted without contacting said surfaces.

Mounted on the shaft 58 and axially spaced apart from each other are similar circular discs 56 of magnetic material. Twelve such discs are employed in the present embodiment of my invention, such that there is one disc for each continuous controlling signal of invariable tone frequency necessary to be produced. Each disc has a bushing 57 firmly secured to the shaft to insure rotation of said disc with the shaft. These discs are respectively provided with 138, 146, 155, 164, 174, 184, 195, 207, 219, 232, 246 and 260 peripheral teeth as disclosed in the third column from the left in the chart illustrated in Figure 11. Inasmuch as all said discs are fixedly mounted on a single driven shaft 58, it follows that with the shaft operating at a constant angular velocity of 30 R. P. S. the discs, in coaction with pick-up devices to be described presently will respectively produce signals at the tone frequencies of notes of a scale tuned in equal temperament. If the range of the gamut of my instrument is eight octaves, the frequency generated by the 138 tooth disc will be 4140 as compared with 4138.4 frequencies for the note C of said scale. The disc having 146 teeth will generate a signal, the frequency of which is 4380 as compared with the vibration frequency 4384.5 corresponding to the note C# in the eight octave of said scale, and so on, to and inclusive of the disc having 260 teeth and which generates a signal, the frequency of which is 7800 as compared to 7812.3 frequencies corresponding to note B in said eight octave. This is important in that an essential feature of my invention resides in the employment of a simple mechanism by which all of the highest frequencies in each octave can be simultaneously and continuously generated and used to control the twelve first stage oscillators of my improved frequency dividing system which consists of twelve similar sets of oscillators in which the oscillators of each set generate signals in octave relation to each other, i. e. there are twelve sets of oscillators, each set producing signals corresponding to all notes of the same octave letter. Obviously, if the range of the gamut is less than eight octaves, the total number of oscillators per individual cascaded series of oscillators will be reduced accordingly.

Carried by the left hand bar 44 of the magnet supporting frame is a set of six permanently magnetized threaded cores 50 of identical coils of high impedance pick-up magnets. The right hand bar 44 of said frame likewise supports a set of six such magnets, the magnets of said last named set being staggered relative to the magnets comprising said first mentioned set. The tip of the core 50 of each individual magnet is pointed at 51 and disposed parallel to the axis of rotation of an associated toothed disc 56 and

spaced apart from the teeth of said disc. Said core freely passes through its bar 44 and has clamping nuts 52 by which the pointed tip of said core can be spaced any desired distance from the teeth of said disc. Each said coil has an output terminal 55.

By reason of the method of mounting the aforementioned magnet supporting frame, it follows that said frame can be tilted in an orbital path about the axis of the shaft 58, the motion of the tips of the cores 50 being concentric to the discs 56. Secured by nuts 45 to the sides 44 of the magnet supporting frame and preferably at the ends thereof nearest the motor 35 are studs 46. Similar studs 69 are secured to the parallel sides of the motor supporting frame as shown in Figure 6. Coil springs 68 connect the studs 69 with the studs 46 and same serve yieldingly to maintain the magnet supporting frame in a state of perfect equilibrium so that alternating voltage generated at the pick-up magnets will be constant or of invariable frequency.

Mounted in the motor supporting frame are horizontally aligned electromagnets 64, each provided with a soft iron core 66. The broad flat tips of the cores 66 are very closely related to the end frame member 43 and are parallel relative to the outer face of said member. The medial centers of said cores are substantially coincident with the upper edge of said member.

In Figure 14 is shown the control circuit for the pair of magnets 66 in Figure 5. This circuit comprises a transformer 182 having a primary winding 183 and secondary windings 184 and 185. The terminals of the secondary winding 184 are connected to the respective plates of a vacuum tube rectifier 187, the filament of which is connected to said primary winding 185. 192 is a magnet, the coil of which has one of its terminals tapped to the secondary winding 184 and connected with a vibratile reed 190. The other terminal of said coil joins the terminal 189 of coil 195 of one of said magnets 66. The opposite terminal of the coil 195 connects with the secondary winding 185. The terminal 189 is disposed at one side of the reed 190. At the other side of the reed is a terminal 188 of the coil 196 of the other magnet 66, the opposite terminal of said coil 196 connecting with said secondary winding 185. The armature 191 of the reed 190 is inductively related to the tip of the core of coil 192.

When the primary winding 183 of the transformer 182 is connected in circuit with a 115 volt alternating current source, the reed 190 is set in vibration at a rate which is determined by its mass and resiliency. When the reed contacts terminal 189, the circuit containing coil 195 is completed and the coil energized. Similarly, the coil 196 is energized when said reed contacts the terminal 188.

It manifestly follows that due to periodic alternate energization of the magnets 66 and corresponding periodic alternate deenergization thereof, the entire set of pick-up magnets 49 will be rocked first clockwise and then counterclockwise against the normal equalizing tendency of the aforementioned springs 68. In consequence thereof, the frequency of all output controlling signals from the output terminals of said magnets 49 will vary slightly, as distinguished from the invariable or constant frequency of said signals produced when the magnets 49 are at rest or are in a perfect state of equilibrium. In order that the vibrato control circuit can be selectively 75

closed when it is desired to convert the constant frequency output signals into signals, the frequencies of which vary periodically and more or less slightly, a switch 186a is connected in the wire 186 as shown. By reason of this method of periodically varying the frequency of said signals, true vibrato effects are obtained.

Except for certain omissions, the mixing system shown in Figures 8 and 9 is similar to the mixing system shown and described in my co-pending application Ser. No. 283,554, filed July 10, 1939. While I prefer to employ such system, I of course do not wish to be limited thereto, and accordingly reserve the right to substitute therefor any well known system that might possibly serve the purpose intended.

It will suffice merely to describe the system briefly and to point to certain novel features thereof in combination with my improved frequency dividing system herein disclosed and claimed.

I have stated that the frequency dividing system shown in Figure 7 consists of eight vacuum tube oscillators electrically interconnected or coupled together in a cascaded series so that their respective output signals are in octave relation, and that twelve substantially similar systems are employed, whereby all signals at the tone frequencies of a musical scale tuned in equal temperament will be produced and made available for the compounding together of various tonal components. I have also pointed out that if the instrument's gamut has a range of eight octaves, there will be eight oscillators per set of oscillators employed and that if the range embraces a lesser number of octaves, the number of oscillators per set will be correspondingly decreased. I have further stated that the system shown in Figure 7 furnishes signals corresponding to all the A# notes and that the highest frequency or first stage oscillator receives a continuous controlling signal from the pick-up magnet 49 of the A# disc 56 of the signal generating system shown in Figure 5.

In Figure 8, I show three playing keys 119, corresponding to notes A#1, A#2 and A#3 of a single keyboard, it being understood that as many keyboards may be employed as shall be desired.

In Figure 9, three stops 129 of a system of stops are disclosed, such that any individual stop when close circuited in the network will render electrically effective a predetermined number of individual tone signals for the production of a waveform of voltage corresponding to a given timbre.

It now will be observed that of the entire set of eight oscillators shown in Figure 7, only seven thereof are connected in respective keying circuits shown in Figures 8 and 9. That is to say, the second oscillator stage is connected to the resistor 116 of the lowermost contact element 117 of the A#3 playing key. The third stage oscillator is similarly connected to the resistor 116 of the lowermost contact element of the A#2 playing key. In like manner, the fourth oscillator stage is connected to resistor 116 of the lowermost contact element 117 of playing key A#1. The eighth oscillator stage connects with the resistor 116 of the uppermost contact element of the A#1 playing key, the signal from said stage corresponding to the sub-fundamental frequency of note A#1. Stage 1 connects to the second resistor 116 from the top of the set used in association with the A#2 key, thus, the signal from said stage serves as the fundamental of the

A#1 note and as the sub-fundamental of the A#2 note. This is effected by a cross lead 115. Similarly, the various stages are employed in the network so that their signals serve as the fundamental frequencies of some notes and as partials or overtones of other notes.

Conductors 124 in Figure 8 each connect with the ground terminal 111 through a resistor 125. A branch lead 123 from said ground terminal has a contact element 122 for each contact element 117. When a key is elevated, the contact elements 117 thereof engage associated elements 122 so that all elements 117 are at ground potential. When the key is depressed, the elements 117 thereof are moved by the sticker 118 into close circuit with respective contactors 121. Each contactor 121 is electrically connected to an assigned one of the conductors 124, the order of the connections being such that each conductor will have transmitted thereto signals of a particular partial grouping, i. e. all signals of the various fundamental frequencies will be impressed upon the second conductor 124 at the left of the set shown in Figure 8. All second partial signals will be impressed upon the fourth conductor 124 from the left and so on throughout the system of conductors.

Each conductor 124 is connected to a contactor 126. These contactors are arranged in sets, such that there is one such set for each of the stops 129 shown in Figure 9. Each stop comprises a set of contact elements 127 similar in number to the key contact elements 117 for each playing key, and each contact element 127 is normally open circuited relative to an associated contactor 126 and is adapted to be close circuited therewith when sticker 128 is moved in response to motion of the stop from a retired to a drawn position.

In each contact element 127 is a resistor 138 connected by a lead 131 to a preassigned tapped portion of a grading resistor 132, the latter having a terminal 132a connected to ground, as shown. The ground terminal 111 to which one terminal of the grading resistor is connected and the terminal 133 of said resistor are connected in circuit with the conventional signal amplifying system 144 and associated electroacoustic translating means 163 shown in Figure 10.

The resistors 116 are each 2 megohms. The resistors 130 are each .5 megohm. Resistors 125 are each substantially .1 megohm. The resistor 132 is substantially .1 megohm. By calculating the relative values of the aforementioned resistors, true additive effects are had when depressing two or more keys which are simultaneously close circuited with the same signal generating source or when two or more stops are drawn and are close circuited with the same said signal generating source.

In the system disclosed in my copending application Ser. No. 283,554, use is made of electrostatic alternators for the production of various tone signals. By reason of the fact that such alternators were not of the same internal impedance, it was necessary to insert in each alternator and to earth a resistance by which an excess of generated voltage could be discharged to ground, as otherwise, the relative effective voltages from different alternators would be out of musical proportion when the signals were translated into acoustic energy. By discharging unwanted or excess voltage to ground, it was possible properly to voice the instrument. In the instant case, no such resistors are necessary as the voltage levels of the generated signals will be found

to be such that the pitches and intensities for successive notes of the scale are correctly related to each other.

In Figure 12 is diagrammatically illustrated certain of the essential elements hereinbefore described in detail and fully shown in the accompanying drawings. It will suffice briefly to state that the power pack 179 for supplying the various stages of my frequency dividing systems has an input cable 171 from an alternating current supply source and an output 175 for supplying the respective stages. The signal generating system 167 has an input 166 from an alternating current supply source by which current is supplied the motor 35 shown in detail in Figure 5. The output paths 167c from the respective pick-up magnets of said signal generating system are connected with their appropriate filters in the filter system 169 and the output paths 167d from said filters are formed into a cable 170 and the latter accommodated in a rectilinear metallic housing 176. Said paths 167d connect with the control grids of the first stage oscillators of the respective cascaded systems of oscillators as will be understood. The output paths 167f from the oscillator stages connect with their associated playing keys as shown.

In order that any individual set of cascaded oscillator stages can be removed from and reinserted in the system whenever occasion therefor may arise, it will be noted that the twelve sets of stages shown in Figure 12 are arranged in parallel rows of six sets each and separated from each other by the aforementioned housing 176. Each individual set of oscillator stages is detachably connected with said housing by means of any well known plug and socket connectors 176g and 176h.

I have illustrated my invention in certain of its preferred embodiments, but wish it understood that modifications may be made and that no limitations upon my invention are intended other than may be imposed by the scope of the hereto appended claims.

What I claim as my invention is:

1. In an electrical musical instrument, twelve oscillating frequency dividing systems, each system including a plurality of oscillators electrically coupled together in cascade to secure octave separation of their respective output signals, a system comprising twelve generators respectively producing alternating voltages at the tone frequencies of notes of the even tempered musical scale, each generator including a circuit path for conduction of alternating voltage to the highest frequency oscillator of one of said frequency dividing systems, said generators each comprising a fixed part and a rotatable part, and a constant speed motor for simultaneously driving said rotary parts at the same angular velocity.

2. An electrical musical instrument comprising a plurality of frequency dividing systems, each said system having a plurality of oscillators electrically coupled together in cascade to secure octave separation of their respective output signals and including a high frequency first stage oscillator, a system including similar alternators respectively producing alternating voltages at predetermined tone frequencies, an output circuit lead connecting an alternator with the highest frequency oscillator of a respective frequency dividing system, said alternators each including a rotatable part, means for driving the rotary parts of the respective alternators at the

same angular velocity and maintaining the output voltages of said alternators at constant frequency, and means selectively actuatable periodically to vary the frequencies of said output voltages while maintaining said rotatable parts at said constant angular velocity.

3. In an electrical musical instrument, means for generating controlling signals for the first stage oscillators of respective sets of oscillators in which the oscillators of each set are electrically coupled together in cascade fashion to secure octave separation of their respective output signals, said means comprising alternating voltage generators of the same total number as said sets of oscillators and each generating alternating voltage of the frequency at which the first stage of an assigned set of oscillators is intended to oscillate and including a transmission path for conduction of said generated alternating voltage to said first stage oscillator, and means including a single driven element for synchronizing operation of all said generators.

4. In an electrical musical instrument, means for generating controlling signals for the first stage oscillators of respective sets of oscillators in which the oscillators of each set are electrically coupled together in cascade fashion to secure octave separation of their respective output signals, said means comprising rotary alternating voltage generators of the same total number as said sets of oscillators and each generating voltage of the frequency at which the first stage of an assigned set of oscillators is intended to oscillate and including a transmission path for conduction of said generated alternating voltage to said first stage oscillator, and means for synchronizing operation of all of said generators, said synchronizing means comprising a synchronous motor having a single shaft driven thereby for simultaneously driving all of said generators at the same angular velocity.

5. In an electrical musical instrument, means for generating alternating voltages at different tone frequencies and utilizing said voltages continuously to stabilize the first stage oscillators of different sets of oscillators in which the oscillators of each set are electrically coupled together in cascade to lock said oscillators in step with each other and secure octave separation of their respective output signals, said means comprising a separate generator for the first stage oscillator of each set of oscillators, each generator including a rotary part of magnetic material and a permanent pick-up magnet, said magnet including an output circuit path to said first stage oscillator, and means for simultaneously driving said rotary parts at the same angular velocity.

6. In an electrical musical instrument, twelve sets of oscillators, the oscillators of each set of oscillators electrically coupled together in cascade to secure octave separation of their respective output frequencies, an output circuit path from each oscillator, twelve alternating voltage generators, each generator continuously producing alternating voltage of the frequency of the output signal of the highest frequency oscillator stage of a particular set of said oscillators, each generator including a rotary part and a part inductively related thereto, and means for simultaneously driving said rotary parts at the same angular velocity.

7. In an electrical musical instrument, a plurality of sets of oscillators, the oscillators of each set electrically coupled together in cascade and

including a first stage oscillator having an input circuit path, each said oscillator having an output circuit path for conduction of a tone signal to an acoustic translating means, and means for establishing and stabilizing the output frequency of the first stage oscillators and comprising a rotary alternator for and connected with the input circuit path of each first stage oscillator for continuous transmission to said oscillator of a controlling signal and means for constantly operating said alternators, each at the same angular velocity.

8. A device for electrically producing signals adapted respectively to be impressed upon the control grids of the first stages of different sets of vacuum tube oscillators in which the oscillators of each set are connected in cascade to lock same in step with one another and secure octave separation of their output frequencies, a synchronous motor, a rotary shaft directly and continuously operated by and at the synchronous speed of said motor and having a predetermined number of axially related signal generating members, a pick-up device for and inductively related to each signal generating member and provided with a signal transmitting path adapted to be connected to the control grid of the first stage oscillator of a set of such oscillators, means supporting all of said pick-up devices for yielding to and fro motion concentrically of the respective signal generating members, and means for selectively operating said supporting means to effect said to and fro motion of said pick-up devices.

9. A device for electrically producing signals adapted respectively to be impressed upon the control grids of the first stages of different sets of oscillation generators in which the generators of each set are connected in cascade to lock said generators in step with one another and secure octave separation of their output frequencies, a synchronous motor, a rotary shaft directly and continuously operated by and at the synchronous speed of said motor and having a predetermined number of axially related signal generating members, a pick-up device for and inductively related to each signal generating member and provided with a signal transmitting path adapted to be connected to the control grid of the first stage oscillation generator of a set of such generators, means supporting all of said pick-up devices for simultaneous to and fro motion concentrically of the respective signal generating devices, means serving normally yielding to resist to and fro motion of said pick-up devices, and selectively actuatable means for causing said to and fro motion against the normal tendency of said motion resisting means.

10. In an electrical musical instrument employing a plurality of electrical oscillation generators coupled together in cascade to lock said generators in step with one another and secure octave separation of their respective output frequencies and including a first stage adapted to be supplied with a controlling signal, a pulsation generator for supplying said controlling signal and comprising a normally immovable part and a rotary part, the latter inductively related to and serving to produce in the former a controlling signal of predetermined tone frequency, a rotary shaft upon which said rotary part is fixed, a synchronous motor coupled to and driving the shaft at a constant angular velocity, movably mounted means yieldingly supporting said normally immovable part for clockwise and counter-

clockwise motion relative to the axis of rotation of said shaft, a pair of magnets associated with said supporting means, and selectively actuatable means for alternately energizing and deenergizing said magnets to thereby impart the aforementioned clockwise and counter-clockwise motion to said normally immovable part.

11. An electrical pulsation alternator including a pick-up device adapted for oscillatory motion, and means for causing oscillatory motion of said device and comprising a circuit having connected thereto a pair of magnets and a single magnet, a vibratile member having an armature associated with and operated by said single magnet, a pair of make and break contacts connected in said circuit and with the magnets of said pair of magnets to effect alternate energization and deenergization of the latter, and means for periodically exciting said single magnet to operate said armature as aforementioned and periodically vibrate said vibratile member.

12. In mechanism of the class described, a plurality of frequency dividing systems, each of said systems comprising a set of vacuum tube oscillators electrically coupled together to secure octave separation of their respective output frequencies and including a first stage, a system of non-resonant oscillatory circuits such that one each of said circuits is connected with and supplies a respective first stage with a controlling frequency, and means common to all of said circuits for causing oscillation thereof each at a predetermined frequency different from that of any of the others.

13. In mechanism of the class described, a plurality of frequency dividing systems, each of said systems comprising a set of vacuum tube oscillators electrically coupled together to secure octave separation of their respective output frequencies and including a first stage, a system of non-resonant oscillatory circuits such that one each of said circuits is connected with and sup-

plies a respective first stage with a controlling frequency, and means common to all of said circuits for causing oscillation thereof at predetermined tone frequencies and comprising a rotary pulsation alternator for and connected with each individual one of said circuits, and a synchronous motor for simultaneously driving said alternators at a common angular velocity.

14. An electrical musical instrument comprising twelve vacuum tube oscillation generators; twelve rotary pulsation generators, each rotary pulsation generator producing a controlling signal of the tone frequency of one of the notes of the even tempered musical scale; a circuit path connecting each individual rotary alternator with a respective vacuum tube oscillation generator for delivery thereto of a controlling signal; and means common to all of said rotary pulsation alternators for driving same at the same angular velocity.

15. In an electrical musical instrument, a frequency generating system embodying twelve sets of oscillation generators, each set of said oscillation generators comprising similar thermionic valves electrically coupled together in cascade fashion to secure octave separation of their output oscillations and including a first stage upon the control electrode of which controlling impulses are adapted to be impressed, and a frequency controlling mechanism comprising a set of pulsation generators, there being one such impulse generator for each individual first stage oscillation generator, each individual impulse generator comprising a movable part and a part inductively related thereto and provided with an output terminal connected with the control electrode of the first stage of a respective one of the aforementioned sets of oscillation generators; and means common to the movable parts of the individual impulse generators for driving them at the same speed.

JAMES MANATT.
